(57) CLAIM

The ornamental design for a motorcycle cup holder, as shown and described.

DESCRIPTION

FIG. 1 is a front perspective view of my invention;

FIG. 2 is a front elevation view thereof;

FIG. 3 is a right side elevation view thereof;

FIG. 4 is a left side elevation view thereof;

FIG. 5 is a top plan view thereof; and,

FIG. 6 is a bottom plan view thereof.

The broken lines in the Figures are illustrative of environmental structure only and form no part of the claimed design.
